(57) **CLAIM**

The ornamental design for a bottle opener, as shown and described.

DESCRIPTION

FIG. 1 is a perspective view of a bottle opener showing the new design.

FIG. 2 is a perspective view of the bottle opener of FIG. 1 socketed in a base.

FIG. 3 is a front view of the bottle opener of FIG. 1.

FIG. 4 is a rear view of the bottle opener of FIG. 1.

FIG. 5 is a side view of the bottle opener of FIG. 1.

FIG. 6 is an opposite side view the bottle opener of FIG. 1.

FIG. 7 is an enlarged top view the bottle opener of FIG. 1; and,

FIG. 8 is an enlarged bottom view the bottle opener of FIG. 1.

The broken lines are shown for the purpose of illustrating both parts of the bottle opener as well as environmental subject matter. None of the broken lines form part of the claimed design.
